UNITED STATES PATENT OFFICE

2,531,969

WINDOW

Louis O. Chartier, Schenectady, N. Y.

Application April 29, 1948, Serial No. 23,982

2 Claims. (Cl. 20—12)

1

My invention relates to improvements in windows for buildings and the like.

The primary object of my invention is to provide a simply constructed, inexpensive window of the sliding sash type and in which sash balances, such as sash cords and weights or spring balances, are eliminated, the sashes are mounted for easy raising and lowering into different set positions, adequate insulation is attained, and the sashes are easily removed and replaced with less effort and in less time than with conventional sliding sash windows.

Another object is to provide a window constructed and arranged for the attainment of the above objects and embodying improved locking means for the sashes.

Other and subordinate objects, within the purview of my invention, together with the precise nature of my improvements, will be readily understood when the succeeding description and claims are read with reference to the drawings accompanying and forming part of this specification.

In said drawings:

Figure 1 is a view in vertical section of a window constructed in accordance with my invention, in a preferred embodiment thereof and viewed from the outside;

Figure 2 is a view in vertical section taken on the line 2—2 of Figure 1;

Figure 3 is a view in horizontal section taken on the line 3—3 of Figure 1;

Figure 4 is a fragmentary view in vertical section taken on the same line as Figure 2 and drawn to a larger scale to better illustrate the sash lock;

Figure 5 is a view in vertical section taken on the line 5—5 of Figure 1;

Figure 6 is a similar view taken on the line 6—6 of Figure 1;

Figure 7 is a view in perspective of one of the sash guides;

Figure 8 is a similar view of one of the side stiles;

Figure 9 is a view in horizontal section taken on the line 9—9 of Figure 1;

Figure 10 is a view in perspective of one of the sash guide tensioning devices;

Figure 11 is a similar view of one of the sash guide mountings;

Figure 12 is a view in perspective of one of the angle brackets.

Referring to the drawings by numerals, my improved window, as illustrated, comprises a frame designated generally by the numeral 1 and 55

2

which includes a pair of side stiles 2, a header 3, and a sill member 4.

The side stiles 2 are set in from the ends of the header 3 and sill member 4 and have the upper and lower ends thereof mortised into the header 3 and sill member 4, as at 5, 6. Also the side stiles 2 are rabbeted and L-shaped in cross section and have suitably secured to outside edges thereof upright outside strips 7 forming with said stiles 2 vertical channels 8 in confronting faces of said stiles extending from the sill member 4 to the header 5. An outside cross keeper strip 9 extending along the header 3 is suitably secured thereto to depend below the same for a purpose presently clear.

The usual outside trim 10 is suitably fixed to the strips 7, 9 and the usual inside trim 11 to the inside edges of the side stiles 2 and to the header 3 and sill member 4 which carries the usual stool cap strip 11'.

A pair of vertical strip-like sash guides 12 are mounted, as presently described, in the channels 8 to extend from the sill member 4 to the header 3 with a slight clearance at the ends thereof and 25 are tensioned, by means also presently described, to grip therebetween a pair of upper and lower sashes 13, 14 slidable along said guides to raise and lower the same, said guides acting to frictionally hold said sashes, yieldingly, in different raised and lowered positions.

The strips 7, 9 overlap the outer sides of the upper sash 13 and form a seal at the sides of said sash, and also at the top of said sash when the same is closed.

Vertical, half round tongue and groove guiding and insulating connections 15, 15' are provided between the sash guides 12 and the upper and lower sashes 13, 14, the tongues 15 being on the sash guides 12 and the grooves 15' in said sashes.

Insulation strips 16, 17 are set into the top edge of the upper sash 13 and into the bottom edge of the lower sash 14 to seat in longitudinal grooves 18, 19 in the header 3 and sill member 4 respectively.

The mounting for the sash guides 12 comprises studs 20 adjacent the upper and lower ends of said guides having base flanges 21 secured by screws 22 to said guides 12, said studs extending horizontally from said guides through apertures 23 in the side stiles 2 and through guide plates 24 secured to said side stiles 2 by screws 35. Midway of the ends thereof, the sash guides 12 are also mounted on the side stiles 2 by means of pairs of guide studs 26 spaced apart laterally of the side stiles 2 with base flanges 27 secured to

said stiles by screws 28, said studs extending through apertures 29 in said stiles and through guide plates 30 secured to said stiles by screws 31.

A pair of upper and lower coil springs 32, 33 tension the sash guides 12 at the upper and lower ends of said guides. The upper coil spring 33 extends along the header 3 in an upper rabbet 34 therein and is attached at its ends to hook screws 35 extending upwardly from the upper ends of said guides 12 through slots 36 in the header 3. The lower coil spring 33 extends along a bottom channel 37 in the sill member 4 and is attached at the ends thereof to right angle brackets 38 extending outwardly from the lower ends of the sash guides 12 through slots 39 in the side stiles 12, and then downwardly into the sill member 4 into the channel 33 by way of slots 40 in said sill member 4.

Suitable dust guards 41 cover the slots 39 and 40. Coil springs 42 on the guide studs 26, interposed between the base flanges 27 of said studs and the guide plates 30 as supplemental tensioning springs for the sash guides 12 and in the transverse centers of said sash guides to prevent said guides from bending outwardly in the center portions thereof.

A sash lock is provided between the upper and lower sashes 13, 14 comprising a keeper plate 43 set into the lower bar 44 of the upper sash 13 in a recess 45 in said bar. A latch bolt 46 is slidable in the upper bar 47 of the lower sash 14 toward and from said keeper plate 43, and is urged by a coil spring 48 thereon toward said plate 43, the coil spring being housed in a recess 49 in said bar 47 and through which the latch bolt 46 extends. A lateral handle 50 with a hand grip knob 51 thereon is provided on one end of the latch bolt 46 for pulling the same away from the keeper plate 43, said handle 50 working in a notch 52 in said bar 47. The other end of the latch bolt 46 has pivoted thereto, as at 53, a latch plate 54 pivoted, as at 55, on attaching plate 56 secured to the upper bar 47, in any suitable manner, and adapted to be swung by the latch bolt 46, under the urge of the coil spring 48, beneath a hooked edge 57 on the keeper plate 43, whereby said sashes 13, 14 are locked against relative vertical movement from closed position. By pulling on the handle 50, the latch plate 56 may be swung out from under the hooked edge 57 and out of the recess 45 to unlatch said sashes.

As will now be seen, the sash guides 12 grip or clamp the sashes 13, 14 therebetween with sufficient pressure to maintain the same in different raised and lowered positions, but with a yielding friction grip permitting said sashes to be raised or lowered, as may be required. As best shown in Figure 9, the side stiles 2 on the inside of the window are spaced apart a distance equal to the width of the sashes 13, 14, with a slight clearance spacing, so that the sashes 13, 14 may be removed from between said stiles 2 from the inside of the window. In this connection, the sash guards 12 are adapted to be forced into the channels 8 sufficiently to remove the

tongues 14 out of the grooves 15 so that said sashes can be freed for removal from between said sash guides 12.

The foregoing will, it is believed, suffice to impart a clear understanding of my invention, without further explanation.

Manifestly the invention, as described, is susceptible of modification without departing from the inventive concept, and right is herein reserved to such modifications as fall within the scope of the appended claims.

Having described my invention, what is claimed as new is:

1. In a window, a frame including side stiles 15 with inner side channels, a header and a sill member having a bottom longitudinal groove therein, a pair of upper and lower sashes in said frame offset relatively for vertical movement past each other, a pair of upright sash guides between 20 said stiles in the channels thereof and between which both said sashes are interposed and guided therein for vertical sliding movement, means for causing said guides to frictionally grip said sashes yieldingly with sufficient pressure to hold the same stationary when moved vertically into different positions comprising hooks on the upper ends of said guides, a spring extending along the top of said header and connecting said hooks, brackets depending from the lower ends 30 of said guides, and a spring in said groove connecting said brackets.

2. In a window, a frame including side stiles with inner side channels, a header and a sill member having a bottom longitudinal groove therein, a pair of upper and lower sashes in said frame offset relatively for vertical movement past each other, a pair of upright sash guides between 40 said stiles in the channels thereof and between which both said sashes are interposed and guided therein for vertical sliding movement, and means for causing said guides to frictionally grip said sashes yieldingly with sufficient pressure to hold the same stationary when moved vertically into different positions comprising hooks on the upper ends of said guides, a spring extending along the top of said header and connecting said hooks, brackets depending from the lower ends of said guides, and a spring in said groove connecting 45 said brackets, and means for mounting said guides on said stiles for sliding movement thereon to grip said sashes comprising lateral studs on said stiles in the channels thereof and on which said guides are laterally slidable.

LOUIS O. CHARTIER.
